TOBACCO POUCH HOLDER

Charles W. Jones, Jr., Hyattsville, Md.

Application March 22, 1950, Serial No. 151,091

4 Claims. (Cl. 206—1)

1

The present invention relates to improvements in a tobacco pouch holder and has for an object the provision of a device of this kind which is adapted to be supported on the instrument board of an automobile or the like.

Another object of the present invention is to provide an improved tobacco pouch holder capable of securely supporting and retaining a tobacco pouch therein so that a pipe smoker can easily fill his pipe with one hand without dislodging the pouch from the holder.

A further object of the present invention is to provide an improved device of this character into which a tobacco pouch can be readily inserted and easily withdrawn when desired and yet will be firmly retained therein while in use.

A still further object of the present invention is to provide an improved structure which may be quickly and easily mounted upon the instrument panel of an automobile or the like or upon a desk, a wall or a similar structure.

The present invention also aims to provide an improved device of this type which may be made of metal, plastic or the like, which comprises relatively few parts and is economical to manufacture.

In one of its broadest aspects the present invention contemplates the provision of an improved tobacco pouch holder comprising a sheet having a main body portion, a supporting ledge extending forwardly from the lower edge of said body portion at substantially right angles thereto, and a resilient side flange extending forwardly from each side edge of said body portion and disposed in spaced substantially parallel relation to the forward face of the side edge part of said body portion for cooperating therewith to firmly grip therebetween the side edge portion of the tobacco pouch.

With the foregoing and other objects in view, 40 the invention will be hereinafter more fully described and more particularly pointed out in the appended claims.

In the drawings, in which the same parts are denoted by the same reference numerals throughout the several views,

Figure 1 is a perspective view of the improved device constructed in accordance with the present invention illustrated as applied to the instrument board of an automobile and having a tobacco pouch therein,

Figure 2 is a front elevational view of the improved device,

Figure 3 is a top plan view of the same,

Figure 4 is a sectional view taken on the line

4—4 of Figure 3 and looking in the direction of the arrows, and

Figure 5 is a sectional view taken on the line 5—5 of Figure 2 and looking in the direction of the arrows.

Referring more particularly to the drawings, A generally indicates the improved tobacco pouch holder. This holder comprises a plate or sheet of metal, plastic or the like, having a main body portion 10 which is longitudinally curved or bowed as can be seen from Figure 3 of the drawing. This body portion 10 may be oblong in shape and has a length and width substantially the same as a conventional tobacco pouch, generally indicated at B. The lower opposite corners 10 of the body portion 10 are cut away as at 11 to provide a longitudinal extension which is bent forwardly to provide a ledge 12 for supporting the intermediate bottom portion 13 of the pouch 20 B. The ledge 12 extends forwardly from the lower edge of the body portion 10 at substantially right angles thereto. The length of the ledge 12 is slightly less than that of the main body portion 10 and the length of the bottom 13 of the pouch 25 B. The width of the ledge 12 is relatively great so that it will afford a substantial purchase for the bottom 13 of the tobacco pouch B.

At each side the main body portion is bent forwardly and inwardly to provide resilient side flanges 14 and 15. Each of the flanges 14 and 15 is disposed in spaced substantially parallel relation to the forward face of the adjacent side edge part of the body portion 10. The free end portion of each of the flanges 14 and 15 is curved 30 rearwardly towards the forward face of the body portion 10 as indicated at 14a and 15a, respectively, to provide a gripping jaw which cooperates with the adjacent forward face of the main body portion 10 to frictionally grip the tobacco pouch therebetween. Outwardly of the jaws 14a and 15a the spaces 16 and 17 between the forward face of the main body portion 10 and the flanges 14 and 15, respectively, are increased for receiving the side edge portions of the tobacco pouch. It will be noted particularly from Figure 3 of the drawing that the spaces 16 and 17 defined by the flanges 14 and 15 and the corresponding opposed parts of the forward face of the body portion 10 are disposed outwardly of the side edges of the ledge 12. The lower edges of the flanges 14 and 15 and the jaws 14a and 15a terminate short of the ledge 12 as is shown in Figure 2 of the drawing. The free end portions of the jaws 14a and 15a are curved slightly forwardly and these portions are also curved on

their upper ends as indicated at 14b and 15b to prevent the jaws from marring the tobacco pouch.

A safety match box retainer, generally indicated at C, is of substantially U-shape in cross section and comprises a forward leg 18, a rear leg 19 and a bottom connecting member 20. The rear leg 19 may be secured to either of the flanges 14 or 15 and in the present illustration it is secured to the flange 14 by welding or the like, as indicated at 21. The forward leg 18 has its upper edge portion bent rearwardly to provide an overhanging lip 22. The forward leg is also provided with rearwardly extending side flanges 23 which are disposed at substantially right angles to the forward leg 18. An elongated slot 24 is provided in the forward leg of the match container C.

Extending rearwardly from the rear surface of the main body portion 10 are studs or the like 25 each of which is provided with an enlarged head 26. These studs may be formed integral with the body portion 10 or they may be separate elements which are secured to the body portion 10 in any suitable manner. A suction cup 27 having a socket 28 is mounted upon each stud 25 by forcing the suction cup over the stud until the head 26 of the stud is received by the socket 28 of the suction cup 27.

In the use of the device the suction cups 27 may be applied to a supporting surface, such as the instrument board 29 of an automobile or the like. The tobacco pouch B may now be inserted in the holder A by forcing the pouch downwardly between the clamping jaws 14a and 15a until the bottom 13 of the pouch B comes to rest upon the upper surface of the ledge 12. The clamping jaws 14a and 15a will now resiliently but firmly and securely engage the forward wall of the tobacco pouch B adjacent the opposite side edges thereof. The force exerted by the jaws 14a and 15a upon the tobacco pouch in cooperation with the body portion 10 will expand the side edge portions of the pouch. The expanded portions will be received and retained by the spaces 16 and 17 formed by the flanges 14 and 15, respectively, in cooperation with the opposed parts of the body portion 10. In this manner the tobacco pouch B will be firmly and securely anchored in the holder A.

It will be further noted from Figure 2 of the drawing that due to the pressure exerted by the jaws 14a and 15a, the side portions of the bottom 13 of the pouch B will extend downwardly below the ledge 12 outwardly of the side edges of the ledge, as indicated at 13a. Such an arrangement will augment the clamping action of the jaws 14a and 15a to prevent displacement of the pouch B when the user is filling his pipe.

When the user wishes to fill his pipe, indicated at 31, he can do so with one hand leaving his other hand free for other duties, such as driving an automobile or the like. The user will lift the cover 32 of the tobacco pouch B and insert the bowl of the pipe 31 into the pouch for filling the bowl. As the smoker inserts his pipe into the tobacco 33 the forward wall 30 of the pouch is free to bulge forwardly due to the space provided between the jaws 14a and 15a. The rear wall 34 is also free to bulge to some extent due to the curvature of the body portion 10. However, bodily movement of the pouch B is prevented due to the clamping action of the jaws 14a and 15a and the retention of the side edge portions of the pouch in the spaces 16 and 17 and the engagement of the portions 13a of the bottom 13 of the pouch with the side edges of the ledge 12 as explained above. The present tobacco pouch

holder is adapted to be used with tobacco pouches having any conventional type closure, such as zippers or the like.

A book of safety matches, generally indicated 5 at D, may be disposed in the container C by forcing the book D downwardly between the legs 18 and 19 of the container until the lower edge of the book D engages and rests upon the bottom 20 of the container C. The forward leg 18 of the container C is sufficiently resilient that it will engage the book D and the lip 22 will overhang the upper edge of the abrasive supporting element 35 of the book D. The slot 24 of the leg 18 will provide access to the abrasive element on the book D for striking a match 36. The side flanges 23 of the forward leg 18 will engage the side edges of the element 35 to prevent lateral movement of the book D when a match is being struck. It will be noted that the container C is mounted upon the flange 14 in such a position that it will not materially obstruct the space between the jaws 14a and 15a. The cover 37 of the match book D may be folded behind the back of the match book and retained in this position by the flange 14.

It is obvious that various changes and modifications may be made in the details of construction and design of the above specifically described embodiment of this invention without departing from the spirit thereof, such changes and modifications being restricted only by the scope of the following claims.

What I claim is:

1. A tobacco pouch holder for mounting on the instrument board of an automobile or the like comprising a sheet of material having a main body portion, a ledge extending therefrom, a resilient flange extending forwardly from each side edge of the body portion and disposed in spaced substantially parallel relation to the body portion, said flanges having clamping jaws thereon, and a substantially U-shaped match book container having a rear leg secured to one of said flanges and a forward leg having a lip for engaging the upper edge of the match book, said forward leg having a slot therein for affording access to the match striking element, said forward leg also having side flanges for engaging the side edges of the match book.

2. A tobacco pouch holder comprising a main body portion, a ledge extending forwardly from said portion for receiving and supporting the bottom of a tobacco pouch when the back wall of the pouch engages said portion, a resilient flange extending forwardly from each side edge of said portion and disposed in spaced substantially parallel relation to the side edge part of said portion for cooperating therewith to grip therebetween the side edge portion of the tobacco pouch, said flanges being spaced apart to provide an opening forwardly of the body portion to permit the expansion of the front wall of the tobacco pouch when a pipe is inserted into the pouch during the pipe filling operation, and a match book container secured to one of said flanges and substantially clear of said opening and comprising two spaced apart legs for receiving a match book therebetween, one of said legs having a lip for engaging the upper edge of the match striking element of the match book for retaining the match book between said legs.

3. An article of manufacture comprising a flexible pouch of tobacco and a holder therefor and secured thereto, said holder comprising a

sheet having a main body portion, a supporting ledge extending forwardly from said body portion at substantially right angles thereto and contacting and supporting the bottom of the tobacco pouch, an inwardly curved separate resilient side flange extending forwardly from each side edge of said body portion and disposed in spaced substantially parallel relation to the side edge part of said body portion and cooperating therewith, said resilient flanges gripping side portions of the pouch and the tobacco therein, and means for attaching said body portion to a support.

4. An article of manufacture as claimed in claim 3 characterized by the fact that said ledge is of less length than that of the body portion and the tobacco pouch, that the flanges are disposed outwardly of the side edges of said ledge, and that said flanges have their lower edges terminating short of said ledge. 20
